J. A. SNIDER

PUMP

Filed Aug. 26, 1921

201 *Conrad Reed*

Attorney

UNITED STATES PATENT OFFICE.

JACOB A. SNIDER, OF DAYTON, OHIO, ASSIGNOR TO THE UNIFLOW PUMP & MANUFACTURING COMPANY, OF DAYTON, OHIO, A CORPORATION OF OHIO.

PUMP.

Application filed August 26, 1921. Serial No. 495,621.

To all whom it may concern:

Be it known that I, JACOB A. SNIDER, a citizen of the United States, residing at Dayton, in the county of Montgomery and 5 State of Ohio, have invented certain new and useful Improvements in Pumps, of which the following is a specification, reference being had therein to the accompanying drawing.

10 This invention relates to pumps and more particularly that type of pump commonly employed in connection with domestic water systems, although it has a much wider field of utility than domestic systems.

15 One object of the invention is to provide a pump of this character having a very high efficiency and capable of lifting water a relatively great distance.

A further object of the invention is to 20 provide a pump of this character which will operate very quietly.

25 A further object of the invention is to provide a pump of this character which can be very easily assembled and in which the valves are readily accessible for the purpose of cleaning or repairing the same.

Other objects of the invention will appear as the device is described in detail.

In the accompanying drawings Fig. 1 is 30 a longitudinal vertical section taken centrally of a pump embodying my invention; Fig. 2 is a section taken on the line 2—2 of Fig. 1; Fig. 3 is a section taken on the line 3—3 of Fig. 1; and Fig. 4 is a detail 35 plan view of one of the valves.

In these drawings I have illustrated one embodiment of my invention and have shown the same as comprising a housing consisting of a body portion 1 having at 40 its lower edges flanges 2 to which is removably secured a lower portion 3 forming a suction chamber and provided with an inlet port 4. The body portion 1 is also provided at its upper edges with flanges 5 to which is detachably secured 45 an upper portion, or cap, 6 forming a discharge chamber and provided with an outlet opening 7. The discharge chamber is also preferably provided with an air chamber 8. Mounted within the body portion 50 of the housing is a cylinder 9 which in the present instance is arranged horizontally and has mounted therein a piston 10, the piston rod 11 of which extends through a stuffing box 12 in one of the end walls of

the housing and is adapted to be connected with a motor or other suitable operating mechanism. The body portion of the housing is provided at the respective ends of the cylinder 9 with passageways 13 extending transversely thereof, communicating with the respective ends of the cylinder and adapted to connect the same with the suction chamber and the discharge chamber. These passageways are preferably of a relatively small size, which, while ample to permit the flow of the water to and from the cylinder reduces the clearance to such an extent that the piston on its discharge stroke will expel practically all the air from 65 the passageway and will, therefore, on the suction stroke produce practically a maximum suction. In order to reduce the passageways to the desired size the end walls of the body portion of the housing have inwardly extending portions 14 which terminate short distances from the respective ends of the cylinder 9 and the side walls of the body portion are contracted above and below the cylinder, as shown in Fig. 2, to further 70 reduce the size of the passageway. The passageways 13 are enlarged at their lower ends, as shown at 15, to receive suction valves 16, which are mounted on the lower portion 3 of the housing so as to be removable therewith and are arranged directly beneath the respective ends of the cylinders and in line with the respective passageways 13. The upper ends of the passageways are also enlarged, as shown at 75 17, to receive the lower portions of discharge valves 18 which are mounted on the body portion of the housing and extend upwardly into the discharge chamber of the cap 6 and are arranged directly above the respective ends of the cylinder and in line with the respective passageways 13. It will be apparent, therefore, that the water flowing 80 from the suction chamber to the discharge chamber will travel in one direction only, that is, it will flow about the suction valve into the cylinder and thence directly through the discharge valve so that it does not reverse the direction of its movement and in its complete movement through the 85 pump makes but few turns. As a result of the movement of the water in one direction the pump may be operated at a high speed and will operate very quietly, the shock which would be caused by the 90 95 100 105 110

stopping and starting of the liquid in reversing the direction of its flow being wholly eliminated. Further, the arrangement of the valves and the construction of the passageways are such that the clearance at the ends of the cylinder are reduced to a minimum which is just sufficient for the free passage of the water. Consequently, practically all air will be expelled from the passageway upon the discharge stroke of the piston and a very powerful suction will be created upon the suction stroke of the piston. The outer end wall of the housing is provided with a bore in line with the cylinder to permit access thereto and this bore is normally closed by a plug 19 screw threaded into the end wall and terminating substantially flush with the inwardly extending portion of the end wall. An air valve 20 is mounted in the removable lower portion 3 of the housing and communicates with one of the passageways 13 to admit to the pump a limited amount of air which will be forced into the storage receptacle to maintain a proper air pressure therein. It will further be apparent that because of the arrangement of the valves and the construction of the housing the valves are readily accessible. The suction valves are carried by the lower portion of the housing and when this is removed the valves are removed with it so that they are wholly accessible for cleaning or repairing. The discharge valves being mounted on the top wall of the body portion, can be reached by merely removing the cap 6. The whole construction is extremely simple, very compact, and is highly efficient in its operation and will operate with considerably less power than is usually required to operate pumps of a similar or even a smaller capacity.

While I have shown and described one embodiment of my invention I wish it to be understood that I do not desire to be limited to the details thereof as various modifications may occur to a person skilled in the art. 45

Having now fully described my invention what I claim as new and desire to secure by Letters Patent, is: 50

1. In a pump, a housing, a cylinder mounted in said housing, a piston mounted in said cylinder, said housing having a suction chamber beneath said cylinder, and a discharge chamber above said cylinder, the walls of said housing having portions extending inwardly at the respective ends of said cylinder to form relatively small passageways about the ends of said cylinders, 60 which passageways communicate with said suction chamber and said discharge chamber, and valves to control said communication.

2. In a pump, a housing, a cylinder mounted in said housing, a piston mounted in said cylinder, said housing having a suction chamber beneath said cylinder and a discharge chamber above said cylinder, the walls of said housing having portions extending inwardly at the respective ends of said cylinder to form relatively small transverse passageways connecting the respective ends of said cylinder with said suction chamber and with said discharge chamber, 70 and having enlarged end portions, and valves arranged in the enlarged portions of said passageways to control the communication between the same and the respective chambers. 75

In testimony whereof, I affix my signature hereto. 80

JACOB A. SNIDER.
